TELEGRAPHIC PRINTING SYSTEM

James A. Spencer, Teaneck, N. J., assignor to
Radio Corporation of America, a corporation
of Delaware

Application October 11, 1947, Serial No. 779,320

2 Claims. (Cl. 178—35)

1

The present invention relates to telegraphic printing systems and more particularly to printing systems based on the step-by-step method of transmission and reception. That is, the present invention is particularly directed to a printing system which will produce, on a paper tape, a printed record in response to a series of unequal length trains of signal reversals. Similar step-by-step systems which have previously been developed, such as the Healy Stock Ticker and Burry Printer, generally require auxiliary driving, phasing and printing signals or equivalent expedients which increase their complexity and cost.

Thus, an object of the present invention is to produce a simple, low cost machine capable of translating variable length trains of two element code signals into printed records without the use of special driving or phasing signals.

Another object of the present invention is the provision of a simplified telegraphic printer which will operate over long periods of time without requiring expert attention.

Still another object of the present invention is the provision of a telegraphic printer which, at each printing operation, automatically restores itself to a homing position from which position all printing operations are based.

Still another object of the present invention is the provision of a telegraphic printer which is adapted to be operated by signals of a character which may be transmitted over normally unused facilities of a radio broadcasting system. Thus, the printer of the present invention may, for example, be coupled to a farmer's radio broadcast receiver tuned to a station transmitting marketing reports and allowed to operate during the night. Thus, the farmer is provided with complete market reports the first thing in the morning so that he may plan his day's activities in accordance therewith. Since in many such cases commercial power lines are unavailable, it is necessary that such a printer be independent of power line frequencies and that it require little electrical power for its operation. The printer of the present invention fulfills these requirements.

The foregoing objects and others which may appear from the following detailed description are attained by providing a telegraphic printer including an electromechanical device for advancing a carrier having character indicia such as rotating a typewheel on a step-by-step basis in response to the variable length trains of signal reversals. A second electromechanical

means is provided for initiating the printing operation, advancing the recording media and resetting the typewheel to a home position in response to a spacing signal of greater time duration than the normal spacing signal elements in the trains of signal reversals. Thus, after printing each character, the printer is returned to a position of rest forming a base from which the next letter to be printed is established.

The present invention will be more fully understood by reference to the following detailed description which is accompanied by a drawing in which:

Figure 1 illustrates in elevational view an embodiment of the present invention, while

Figure 2 illustrates a cross sectional view of the device taken along line 2, 2 of Figure 1;

Figure 3 is an end view of the device of Figure 1;

Figure 4 is a sectional view taken in the direction of the arrows 4, 4 of Figure 2;

Figure 5 is a fragmentary view showing, in section, the spring return for the typewheel of the device of Figure 1, while

Figure 6 is an electrical circuit diagram of the invention.

Referring now to Figure 1 there is shown a base member generally indicated by reference character 10 carrying a vertical supporting plate 12 on which is mounted a typewheel shaft 14. Shaft 14, as shown in more detail in the section of Figure 2, carries a type carrier in the form of a typewheel 15 thereon. Typewheel 15 is urged to a position of rest by spring 16 attached at one end to the hub 15' of typewheel 15 and at the other end to a spring barrel 18. As shown in detail in Figure 5 spring barrel 18 is secured to the vertical support member 12 by clamp dogs 19 and screws 20. By loosening screws 20 the spring barrel 18 may be rotated as desired in order to increase or decrease the tension on spring 16 acting to return the typewheel 15 to its homing position. Typewheel hub 15' carries, in addition to the typewheel, an operating ratchet wheel 21 and a stop member 22 (Fig. 1). The typewheel is rotated by a mechanism to be described later, operating against ratchet wheel 21. In the position of rest the stop member 22 bears against a fixed stop 23 mounted on the supporting plate 12. The stop may be faced by resilient material acting to cushion the blow of the stop member 22 striking the stop 23. The stop pin 22 also normally rests against the lower contact spring leaf 24 moving its contact

24 away from the contact carried by spring 25. These contacts are thus closed only while the typewheel is away from its home position. The contacts are thus shown in Figure 4.

A magnet 30 having an armature 32 is mounted on the vertical supporting plate 12. The armature 32 carries a ratchet pawl 33 adapted to cooperate with ratchet wheel 21. When the magnet 30 is energized, armature 32 is attracted against the tension of spring 34, pressing pawl 33 against a tooth on ratchet wheel 21, rotating it clockwise against the tension of spring 16. Pawl 33 wedges under a stop 35 at the end of its travel, jamming the ratchet wheel against further rotation and thus preventing 15 overfeeding. A second pawl 36 engaging with ratchet wheel 21 and journaled on support 12 is provided to hold the wheel in its advanced position after pawl 33 is withdrawn by the action of spring 34 when magnet 30 becomes de-energized. In order to prevent excessive rotation of the typewheel so that stop member 22 jams against the back of stop 23, one or more teeth may be omitted from ratchet wheel 21 in such position that excessive rotation is prevented.

The angular movement of ratchet wheel 21 about the typewheel shaft 14 positions a selected one of the typefaces on the periphery of typewheel 15 over a platen or print roller 40. Recording media such as record tape 42 coming from reel 44 threads through guides 45 between the print roller and the typewheel 15. After passing through the second guide 45 the record tape passes between a pair of feed rollers 46 and 47. Tape feed roller 47 is carried by a pivoted carriage 49 and resiliently pressed against the feed roller 46 by means of spring 48. Feed roller 46 journaled on support 12 carries a ratchet feed wheel 50. Ratchet wheel 50 is adapted to be rotated by the action of pawl 51 engaging the teeth on the ratchet wheel 50 as pawl 51 is moved by the operation of armature 52 on which it is pivoted. Armature 52 is pivoted on support 12 at 56 and is arranged to be swung in a clockwise direction by magnet 54 against the tension of spring 53. The print wheel 40 is carried by an arm 55 also pivoted on spindle 56. Arm 55 is thus adapted to be pressed upwardly so that platen 40 presses the record tape 42 against a selected type character on wheel 15 whenever magnet 54 is energized.

As shown in Figure 6 the winding of magnet 54 is connected in series with the contact springs 24 and 25 and the armature 61 of a slow-to-release relay 60 to a source of potential as indicated by the plus mark. When the ratchet and typewheel occupies a homing position, the contacts carried by springs 24 and 25 are separated and the circuit through the printing magnet 54 cannot be completed, whatever the condition of relay 60. The signal input is applied to a series circuit running through the winding of the slow-to-release relay 60, and the winding of the stepping magnet 30 to ground. The incoming selecting signals of the character indicated at the upper left-hand portion of Figure 6 are comprised of square wave impulses having marking and spacing elements of approximately equal time duration. Relay 60 is adjusted to operate and open its contacts 61 in response to a single marking signal element and to remain operated for a period of time greater than that of one spacing element. Magnet 30 is adjusted to operate and release in response to the marking and spacing elements. The contacts carried

by springs 24 and 25 close as soon as stop pin 22 leaves its homing position against stop 23, so that whenever ratchet wheel 21 is advanced through the action of pawl 33 and armature 32 10 the printing circuit is completed from the moving contact of relay 60 through contacts 24 and 25, through coil 54 to ground. Since the windings of relay 60 and magnet 30 are connected in series, the signals that actuate magnet 30 also actuate relay 60 to open its contacts. The relay 60 being so adjusted as to release only in response to spacing elements existing for a time duration substantially greater than that of a normal spacing element, the printing circuit remains open at the contacts of relay 60 during the reception of each series of selecting impulses. At the conclusion of each train of impulses, a spacing signal of substantially greater than normal time duration is received. The relay 60 then releases and causes magnet 54 to be energized and initiate the printing operation. The energization of magnet 54 causes the tape roller 40 to press the record tape 42 against the selected one of the type characters on typewheel 15. The operation of armature 52 likewise causes pawl 51 to be stepped upwardly one tooth on ratchet 50. The printing operation also causes locking pawl 36 to be withdrawn from ratchet wheel 21, allowing the typewheel to return to its home position. The stop 22 striking contact spring 24 opens the printing circuit and allows armature 52 to fall back. The return of armature 52 to its normal (at rest) position, rotates the tape feed roller 40 to advance the record tape to a new printing position.

The type on print roller 15 is preferably arranged in accordance with the frequency of occurrence of letters in the type of messages most likely to be transmitted so that a minimum number of selecting impulses is required for the most commonly used letters. The typefaces may be inked by an inking roller 10 carried by a pivoted carriage 11 urged against the typewheel by gravity or a light spring if desired. Alternatively, a strip of carbon paper may be carried along with, but preferably at a slower rate than, the record tape 42.

While I have illustrated a particular embodiment of the present invention, it should be clearly understood that it is not limited thereto since many modifications may be made in the several elements employed and in their arrangement and without departing from the spirit and scope of the invention.

What is claimed is:

1. A teleprinter including a typewheel having printing characters on its periphery, a record tape, resilient means for urging said typewheel to a predetermined home position, a ratchet wheel carried with said typewheel, signal input means and a series circuit across said signal input including a signal responsive magnet and a slow-to-release relay, a pawl actuated by said magnet and engaging said ratchet so arranged as to step said typewheel away from its home position in response to signal impulses applied to said input means, a printing bar and electro-magnetic actuating means for said printing bar, a circuit including a back contact of said slow-to-release relay and its armature, a pair of contacts adapted to be closed by movement of said typewheel away from its home position and said electro-magnetic actuating means, said slow-to-release relay closing said circuit in response to cessation of each train of signal impulses whereby said printing

bar is actuated, means responsive to actuation of said printing bar for releasing said typewheel for return to its home position and means responsive to the release of said printing bar for feeding said record tape, said last mentioned means including a feed roller for said record tape, a ratchet on said feed roller and a feed pawl adapted to engage said ratchet and operated by said printing bar.

2. A teleprinter including a typecarrier having type faces arranged in sequence thereon, a recording medium, resilient means for urging said typecarrier to a predetermined position, a ratchet carried with said typecarrier, signal input means and a series circuit across said signal input including a signal responsive magnet and a slow-to-release relay, a pawl actuated by said magnet and engaging said ratchet so arranged as to step said typecarrier away from its home position in response to signal impulses applied to said input means, a platen and electromagnetic actuating means for said platen, a circuit including a back contact of said slow-to-release relay and its armature, a pair of contacts adapted to be closed by movement of said type carrier away from said predetermined position, and said electromagnetic ac-

tuating means, said slow-to-release relay closing said circuit in response to cessation of each train of signal impulses whereby said platen is actuated, means responsive to actuation of said platen for releasing said typecarrier for return to said predetermined position and means responsive to the release of said platen for feeding said recording medium, said last mentioned means including a feed roller for said recording medium, a ratchet on said feed roller and a feed pawl adapted to engage said ratchet and operated by said platen.
